UNITED STATES PATENT OFFICE

165,944

COMBINED SERVING CART AND TABLE

John Strathaus, Los Angeles, Calif.

Application June 12, 1951, Serial No. 15,509

Term of patent 14 years

(Cl. D33—14)

To all whom it may concern:

Be it known that I, John Strathaus, a citizen of Germany, residing at Los Angeles, in the county of Los Angeles and State of California, have invented a new, original, and ornamental Design for Combined Serving Cart and Table, of which the following is a specification, reference being had to the accompanying drawing, forming a part thereof.

I claim:

The ornamental design for a combined serving cart and table, substantially as shown.

JOHN STRATHAUS.
